United States Patent [19]

Moraine

[11] Des. 273,294

[45]  Apr. 3, 1984

[54] DIRECTORY TERMINAL

[75] Inventor: Michel Moraine, Boersch, France

[73] Assignee: La Telephonie Industrielle et Commerciale, Strasbourg, France

[] Term: 14 Years

[21] Appl. No.: 239,037

[22] Filed: Feb. 27, 1981

[30] Foreign Application Priority Data

Aug. 29, 1980 [FR] France 80 2725

[52] U.S. Cl. D14/101; D14/106

[58] Field of Search ..... D14/100-117, D14/58; 364/900; 340/700, 711, 365 R; 179/1 MN, 100 R, 100 D, 179

[56] References Cited

U.S. PATENT DOCUMENTS

D. 226,920 5/1973 Molyneaux D14/101

D. 244,464 5/1977 Davis, Jr. D14/106

OTHER PUBLICATIONS

Computer Design, Jan. 1980, p. 14, VAX-11/780 Computer.

Datamation, Nov. 1975, p. 89, Bell System "Transaction" Telephone.

Primary Examiner—Susan J. Lucas
Attorney, Agent, or Firm—Kenyon & Kenyon

[57] CLAIM

The ornamental design for a directory terminal, as shown and described.

DESCRIPTION

FIG. 1 is a front perspective view of a directory terminal showing my new design;

FIG. 2 is a left side perspective view thereof;

FIG. 3 is a right side perspective view thereof;

FIG. 4 is a left front perspective view thereof;

FIG. 5 is a rear elevational view thereof; and

FIG. 6 is a right side elevational view thereof.

Fig. 3.

Fig. 5.

Fig. 6.